WESTERN SADDLE

Leo V. Houy, Pueblo, Colo.

Application July 29, 1955, Serial No. 37,213

Term of patent 7 years

(Cl. D38—15)

Fig. 1 is a side elevational view of the western saddle embodying my new design;

Fig. 2 is a side elevational view looking from the other side thereof;

Fig. 3 is a front elevational view;

Fig. 4 is a rear elevational view;

Fig. 5 is a top plan view; and

Fig. 6 is a bottom plan view thereof.

I claim:

The ornamental design for a western saddle, substantially as shown.
